UNITED STATES PATENT OFFICE.

CARLETON ELLIS, OF MONTCLAIR, NEW JERSEY.

PROCESS OF HYDROGENATING OIL MIXTURES AND THE LIKE.

1,078,136.

Specification of Letters Patent.

Patented Nov. 11, 1913.

Application filed September 10, 1912. Serial No. 719,541.

To all whom it may concern:

Be it known that I, CARLETON ELLIS, a citizen of the United States, and a resident of Montclair, in the county of Essex and State of New Jersey, have invented certain new and useful Improvements in Processes of Hydrogenating Oil Mixtures and the like, of which the following is a specification.

10 This invention relates to an oily or fatty product preferably or specifically consisting of a mixture of treated oils or fats and to the process of making same all as more fully hereinafter described and as claimed.

15 Reference to the accompanying diagrammatic drawings makes clear the manner in which the process herein may be carried out.

In the drawings Figure 1, shows a treating tank in vertical section, while Fig. 2 20 illustrates by sectional view a modified form of apparatus applicable in the treatment of certain fats.

Like reference characters designate like parts throughout.

25 In Fig. 1, a treating tank 1 (preferably cylindrical) is surmounted by a spraying dome 2. The tank is provided with the heating jacket 3, oil inlet pipe 4, gas exhaust pipe 5, plugged aperture 6, oil outlet pipe 7, and manhole 8. The dome 2 also is provided with a manhole 9. 10 is a gas exit, at which point the intake of the pump 11 communicates with the upper part of the tank 1. From this pump a delivery pipe 30 12 extends to the bottom of the tank and connects with the gas distributers 13 and 14 which are tubular in form and are situated in preferably radial position at or near the bottom of the tank. Outlets or nozzles 35 12 preferably laterally disposed afford exits for the gas into the tank at this point. A larger number of outlets or nozzles is provided on one side of each distributer than on the other. Thus by the greater lateral 40 ejection of the gas on one side than on the other the body of oil largely filling the tank 1 is given a rotary motion while the lesser number of opposing jets on the opposite side of the distributer being directed 45 into and against a constantly advancing current of oil afford a degree of impingement which greatly lends to the hydrogena-

tion of fatty mixtures difficult of rapid treatment in other ways. This opposed differential ejection of the gas therefore constitutes an important feature of the apparatus involved in the process as concerned under Fig. 1. 15 is a branch outlet gas pipe leading from the pump 11 to the inspirators and atomizers 16, and terminating 55 as concentrically disposed nozzles 21 within the said inspirators. A pipe 17 extends from near the bottom of the tank to these inspirators and enables the oil or fatty mixture to be entered thereinto. 18 60 is a pump whose inlet communicates with the pipe 17 and whose outlet by means of the pipe 19 connects with the inspirators 16. In the lower part of the dome are a series of screens or perforated metal sheets 20 spaced 65 slightly apart. At 20^a are shown pipes for the admission of superheated steam for de-colorizing purposes or otherwise as will be hereinafter set forth.

In the operation of the process in accordance with Fig. 1 the oily material is entered by the pipe 4 until the tank is about two-thirds filled. Steam is passed through the jackets 3 to heat the oil to the treating temperature. Any air contained in the tank 70 and connections is preferably removed by passing hydrogen or water-gas therethrough while the oil is being treated. Catalyzer, preferably in a very finely divided form is entered by the aperture 6. The operation of 75 the pump 11 causes gas to be withdrawn from the top of the tank and to be propelled into the distributers 13 and 14 and from thence into the body of oily material causing rotation thereof and differential impingement as aforesaid. Gas passing through the pipe 15 into the inspirators 16 causes oily material and catalyzer to be propelled from the bottom of the tank 1 into the inspirators. The material mingles with 80 the gas and is ejected from the inspirators. These as shown are arranged radially opposed so that the atomized jets mutually impinge and the component parts of the jets thus become further commingled. The oil 85 fog produced, in its atmosphere of hydrogen passes through the screens 20 and through the special heating zone engendered by the heating pipes or coil 20^a, finally col-

lecting in the tank 1. This cycle is repeated or continued until the material has become hydrogenated to the degree desired, when the tank is emptied of its oily contents by the outlet 7. Optionally the pump 18 may be used to cause a more rapid circulation of the oily material, but when the catalyster is of a gritty nature, abrasive action may preclude such use. Gritty particles do not, however, interfere with the operation of the inspirators 16 under the gas pressure developed by the pump 11.

As indicated, the apparatus of Fig. 2 is perhaps of more specific application than that of Fig. 1 in carrying out the process of the present invention. In Fig. 2, 1 is a treating tank preferably as shown of conical shape. It is provided with a stationary mass of catalyster 31 resting on a grid 29. 32 is a manifold carrying a series of downwardly depending nozzles or atomizers. 30 is an upwardly directed jet or nozzle for entry of hydrogen gas. In the operation of the process hereunder oil is continuously circulated by means of the pump 18 through the porous bed of catalyster 31. The spraying device 32 enables the oil in a finely divided condition to come into intimate contact with the catalyster and the counter-current of hydrogen or similar gas. A heating zone preferably somewhat localized is maintained by the heating pipes 20. The coning or taper of the tank is preferably adjusted so that the mass of catalyster contracts with respect to the degree of gradual agglomeration of the spray particles, thereby enabling thorough contact of the oily material, gas and catalyster to effectively take place.

While the foregoing process is applicable to the treatment of oils of a unitary chemical composition it is more particularly or specifically adapted to the hydrogenation of oily or fatty materials of a composite nature including mixtures of oils of differing origin and chemical constitution such as admixed vegetable oils or some of their components, admixed animal oils and admixed animal and vegetable oils.

With certain oils the hydrogenation progresses rapidly for a time and then proceeds very slowly, other oils hydrogenate rapidly to a high degree of hardness in a much shorter time. The hydrogenation of mixtures of oils to secure the desired degree of hydrogen addition throughout the several unsaturated bodies which may have been present in the raw mixtures apparently cannot be carried out by the present known methods of hydrogenation in a thoroughly controllable manner as is possible with a unitary body such as oleic acid. The present process enables such mixtures of oily material to be readily hydrogenated to the desired extent, and in a certain measure enables selective hydrogenation to be under

control. Linoleic and linolenic acids or esters which take up hydrogen readily when the latter is bubbled through the former under otherwise suitable hydrogenating conditions do not require atomization for effective contact with hydrogen, but some oleic esters which are slower of hydrogenation may be usefully atomized in the foregoing manner. Hence the treatment of complex mixtures by the process enables some measure of selective hydrogenation to be practised with desirable results. As an illustration it may be stated that palm oil which is practically unfit for edible purposes owing to its rank odor and disagreeable taste may be converted into a clean smelling fat possessing a faint spicy to coffee-like odor and improved flavor. So persistent is the odor of ordinary palm oil that when made into soap the saponified product retains the original disagreeable odor of the oil unchanged. By my process palm oil may be so freed from odor that it cannot be recognized in soaps by odor and the hydrogenated and saponified product yields an improved lather and detergent properties of a desirable character. The potash and soda soaps are especially useful. A suitable soap may be made by hydrogenating a mixture of equal parts cotton-seed and palm oil and saponifying 100 parts of this mixture with 11 parts of caustic soda and 13 parts of caustic potash. Other soap stock mixtures are palm oil 1 part, cotton-seed oil 3 parts; palm oil 1 part, corn oil 2 parts, tallow 1 part; palm oil 1 part, horse fat 1 part and cotton-oil foots or distilled fatty acids 1 part. Owing to the albuminous matters and large proportion of free acids and other bodies produced by rancidification, palm oil is destructive to some catalysters. Palm oil oftentimes shows a fatty acid test indicative of a 50% or more of free fatty acids. It is not desirable to hydrogenate with this high proportion of acids present for the best results, but preferably the acidity of the oil should not exceed 25 or 30%. By diluting a high acid oil with an oil with which it is to be associated ultimately in edible products, soaps or other materials, action on the catalyster is reduced to a minimum. In the case of nickel catalyster or other similar metal catalyster present in a finely divided condition an oil having this excess of free fatty acid is objectionable, because of the possibility of solution of the nickel or other metal by the acid, especially when hydrogenating at a high temperature and in such a case the free acid should be reduced proportionately. For hydrogenating at relatively low temperatures, the presence of 20 to 30% of the free fatty acid does no harm according to my experimental observations. I have found rancid palm oil running up to 30 to 33% of free fatty acid to hydrogenate very 130

rapidly even at a temperature of 190° in the apparatus described in my U. S. Letters Patent No. 1,026,156 of May 14, 1912. Palm oil is capable of being decolorized by heating, a temperature of 240° or higher being used for this purpose. Decolorization at this high temperature especially in the presence of air or oxygen leads to further decomposition of the oil and increased formation of free fatty acids. By decolorizing in an atmosphere of an inert gas further rancidification is substantially prevented. Hydrogen is suitable for this purpose so that the operation of decolorization and hydrogenation may be carried out simultaneously to advantage.

For the manufacture of edible oils it is undesirable to continuously heat the oil to the decolorization temperature which in the case of palm oil in the presence of hydrogen is about 190° C. By the present process a decoloring zone of somewhat higher temperature may be maintained locally in the apparatus and while the major portion of the hydrogenation normally goes on at the desired relatively low temperature, the localized heating zone effects the decolorization under perfectly controllable conditions. Sometimes the treating tank has, however, to be reduced in temperature after hydrogenation and decolorization have gone on to some extent, and for this purpose a cooling fluid may be passed through the heating jacket shown in the Fig. 1, while maintaining the high temperature heating zone within the mass of screen material in the atomizing dome. At a temperature of 190° maximum, palm oil of about 25% or so acidity is hydrogenated to bring its original titer 86.4° F. up to 96.8° F. and the color is changed from a deep orange to a pale yellow. An intermediate body having a titer of 91 is suitable for and as an addition to other oils in the manufacture of butter substitutes. The titer herein is that of the oil and not that of the fatty acid. The product of a titer of 96.8° F. makes an excellent soap material and the soap produced is free from the disagreeable odor of crude palm oil.

Wherever the term oil or fat has been used herein, it should be understood that for the purpose set forth these terms are used as substantially synonymous.

The gas pressure which may be employed in treating the oil or fat in accordance with the present process is variable depending upon the character of the product required. In the manufacture of edible products low pressure and low temperatures preferably should be employed in order to avoid the formation of lactones. However, these depend to a certain extent on the oil which is being treated and the temperature and pressure may therefore be regulated with respect to this consideration. In the manu-

facture of soap stock the presence of lactones is not of so much importance and high pressures and relatively high temperatures may be employed without material sacrifice in the quality of the product as regards the purpose to which it is to be applied.

By the present process vegetable oils such as corn, peanut, cotton-seed, rape, linseed, Chinese wood, castor, cocoanut, sesame, soy bean, and other vegetable oils separately or in admixture may be effectively treated; also marine oils such as menhaden, codliver oil, whale oil and other fish oils; also animal oils such as oleo-stearin, tallow and lard oil, horse oil, tankage grease oil foots and the like. Oil foots are usually very difficult to hydrogenate owing to the high percentage of impurities, some of which act as a poison on catalysts under most circumstances. By dilution of foots with 2 or 3 parts of oil with which the foots are ultimately to be associated, as in soap, lubricants and the like, the hydrogenation process often may be carried out with ease. Thus oils and fats which are so impure as to be practically incapable of hydrogenation and which are furthermore often incapable of being refined without excessive cost, may, under the present process, be hydrogenated without any especial preliminary refining, it being only necessary to determine the ultimate use of the impure oil and the extent to which it is to be incorporated with other oils and to then make a composition approximating this composition and hydrogenate same.

What I claim is:—

1. The process of hydrogenating composite fatty material and the like which comprises diluting an acid oil with a substantially neutral oil and in subjecting the mixture to hydrogen in the presence of a catalyst.

2. The process of hydrogenating composite fatty material and the like which comprises diluting an acid oil with a substantially neutral oil and in subjecting the mixture to a hydrogen-containing gas in the presence of a catalyst.

3. The process of hydrogenating composite fatty material and the like which comprises diluting a substantially catalyzer-toxic oil with a substantially neutral oil and in subjecting the mixture to a hydrogen-containing gas in the presence of a catalyst.

4. The process of hydrogenating composite fatty material and the like which comprises diluting a substantially catalyzer-toxic oil with a substantially neutral oil and in subjecting the mixture to a hydrogen-containing gas under pressure in the presence of a catalyst.

5. The process of hydrogenating composite fatty material and the like which comprises the sub-process of prior to hydrogenation diluting an oil-containing material

inhibiting catalyster activity with another oil substantially free from inhibiting bodies.

6. The process of hydrogenating composite fatty material and the like which comprises diluting an oil containing catalyster poison with another oil free from catalyster poison and in atomizing the mixture with hydrogen in the presence of a catalyster.

Signed at Montclair in the county of Essex and State of New Jersey this 9th day 10 of September A. D. 1912.
